CLAIM

The ornamental design for a combined wire and bolt pliers, substantially as shown and described.

DESCRIPTION

FIG. 1 is a plan view of one side of the combined wire and bolt pliers showing my new design;
FIG. 2 is a side elevational view of FIG. 1;
FIG. 3 is a plan view of the bottom side of FIG. 1; and
FIG. 4 is an end elevational view of the right end of
FIG. 1.
